United States Patent Office

Des. 211,277
Patented June 4, 1968

211,277

PATH LIGHT

Christopher C. Layton, San Francisco, Calif., assignor
to Filper Corporation, San Ramon, Calif., a corpora-
tion of California

Filed Feb. 20, 1967, Ser. No. 5,879

Term of patent 14 years

(Cl. D48—31)

FIG. 1.

FIG. 2.

FIG. 3.

FIG. 1 is a side-elevational view of a path light embodying my new design, the other two lateral sides and the opposite side being the same.

FIG. 2 is a top plan view thereof.

FIG. 3 is a bottom plan view thereof.

I claim:

The ornamental design for a path light, substantially as shown.
